GUN SIGHTING DEVICE.

1,158,926.

Specification of Letters Patent.

Patented Nov. 2, 1915.

Application filed August 25, 1914. Serial No. 858,522.

To all whom it may concern:

Be it known that I, HEINRICH JUST, a citizen of the German Empire, residing at Essen - on - the - Ruhr, Germany, have invented certain new and useful Improvements in Gun Sighting Devices, of which the following is a specification.

The subject matter of the present invention is a gun sighting device having an arrangement for automatic correction of the firing angle, when a point is to be aimed at which is situated a certain known distance above or below the point to be fired at.

One embodiment of the invention is illustrated in the accompanying drawing as a sighting device, which is provided with an index, adjustable from a controlling station, in accordance with the range, and

Figure 1 shows a side view of the sighting device; Fig. 2 a section along line 2—2 of Fig. 1 seen from above and Fig. 3 a section along line 3—3 of Fig. 2 seen in the direction of arrow α .

A housing A for the sighting device, which is provided with a telescope, not shown, is rigidly secured on the cradle in which the gun in the usual manner is made to slide, the gun and the cradle not being shown.

The telescope is mounted on the head of the sight rack B which is adjustably carried in the housing A. To set the sight line at the angle between the sight line and the axis of the bore, which angle corresponds to the range, a worm C is provided having a hand wheel C^1 , which worm is revolvably mounted in the housing A. The worm C is in mesh with a worm wheel D, which is rigidly connected with a spur wheel D^1 engaging with teeth b^1 of the sight rack. On the worm shaft is also provided a second worm C^2 in mesh with a worm wheel E, Fig. 3, which is loosely mounted on a journal F rigidly connected with the housing A. A small electric motor G, Fig. 2, is secured on the worm wheel E eccentrically to its axis of revolution, which motor acts as receiver for a remote electric control. The shaft of the electric

motor G is provided with a self locking worm g^1 , which is in mesh with a worm wheel H freely revoluble on the journal F. With the worm wheel H an index h^1 is rigidly connected which may register either with a fixed mark a^1 on the housing A, see Figs. 1 and 2, or with a movable mark i^1 ,

Fig. 1, the latter mark being carried by a disk J, which is revoluble independent of the worm wheel H and coaxial therewith. The disk J with the mark i^1 has a tooth 60 sector i^2 meshing with a pinion k^1 carried at one end of a shaft K, mounted in bearings in the housing A. At its other end, the shaft carries a second pinion k^2 , Figs. 2 and 3, driven by a rod M, slidably mounted in 65 the housing A, this rod being provided at one end with teeth m^1 , Fig. 3, meshing with the pinion k^2 . At its other end, the rod carries a projection m^2 , Figs. 2 and 3, which engages with a spiral groove n^1 of a disk 70 N, which is rigidly connected in an easily detachable manner, with the worm wheel D.

The fixed mark a^1 is used when the point to be hit is aimed at, but the movable mark i^1 , when a point of different altitude than 75 the one to be hit, is aimed at, which former point may for instance be situated 10 meters above the latter part.

In the first instance the sighting is done in the following manner. The controller 80 at the remote electric controlling station is first set to correspond to the range of the target. This setting causes a turning of the driving shaft of the electric motor G, which turning is transmitted to the index h^1 85 through the worm gear g^1 H. The index h^1 thus receives an angular position that corresponds to the range of the target relative to the worm wheel E, which is rigidly connected with the motor housing. The 90 worm wheel E, together with the motor G and the index h^1 , which is coupled to the worm wheel E through the self locking worm gearing g^1 H, are now moved by turning the hand wheel C^1 , until the index h^1 95 registers with the mark a^1 . The turning of the hand wheel C^1 is simultaneously transmitted, by means of the gears C, D, D^1 , b^1 , to the sight rack B, in such a manner, that the sight line receives an inclination 100 relative to the axis of the bore, corresponding to the range of the target.

In the second instance, that is, when the point to be hit is not aimed at but a point situated 10 meters above the same, the sight line for the same range to the target, after adjustment of the sighting device must then form an angle with the axis of the bore, which angle is a certain amount smaller than the angle in the first mentioned instance. The magnitude of this amount is only dependent on the range, for a

certain constant difference in height, and it diminishes with increasing range. By suitable selection of the shape of the cam groove n^1 , it is obviously quite easy to 5 arrange so that the movable mark i^1 , when the sighting device is adjusted by means of the gearing N n^1 m^2 M m^1 k^2 K k^1 i^2 actuated by the turning of the hand wheel C^1 , is always turned relative to the fixed mark 10 a^1 exactly such an amount, that the sight line with regard to the above mentioned difference in height, receives the correct inclination to the axis of the bore, if the index k^1 previously adjusted as in the first 15 instance relative to the worm wheel E to correspond to the range of the target, is now made to register with the movable mark i^1 instead of with the fixed mark a^1 .

As for each difference in height, a different 20 shape of the cam groove will appear, a special disk N with correspondingly shaped cam grooves must naturally be provided for each difference in height, in case several such differences are to be used, so that when 25 necessary, the easily detachable disk N may be replaced by another.

I claim:—

1. A gun sighting device having an index, a movable mark with which said index is 30 made to register when the sight is aimed at a point of different height than the point to be fired at; a drive for setting the sight to the firing angle, and a gearing positively connected to said drive for giving said index 35 and said movable mark an adjustment relative to each other, the amount of said adjustment being inverse to the range.

2. A gun sighting device having an index, a fixed mark with which said index is made 40 to register for direct firing; a movable mark with which the index is made to register when the sight is aimed at a point of different height than the point to be fired at; a drive for setting the sight to the firing angle, 45 and a gearing positively connected to said drive for giving said index and said movable mark an adjustment relative to each other, the amount of said adjustment being inverse to the range.

3. A gun sighting device having an index, a fixed mark with which said index is made 50 to register for direct firing; a movable mark with which the index is made to register when the sight is aimed at a point of different height than the point to be fired at; a drive for setting the sight to the firing angle, 55

and a gearing positively connected to said drive for giving said index and said movable mark an adjustment relative to each other, the amount of said adjustment being inverse 60 to the range said gearing also adjusting said movable mark relative to the fixed mark.

4. A gun sighting device having an index, a fixed mark with which said index is made to register for direct firing; a movable mark 65 with which the index is made to register when the sight is aimed at a point of different height than the point to be fired at; a drive for setting the sight to the firing angle, and a gearing positively connected to said 70 drive for giving said index and said movable mark an adjustment relative to each other, the amount of said adjustment being inverse to the range, said gearing having a revolute member and means for turning 75 said member an angle corresponding to the firing angle; a carrier for said movable mark, said carrier being coaxially mounted with said index, said carrier having teeth, a pinion meshing with said teeth and means 80 positively connected with said drive for turning said pinion.

5. A gun sighting device having an index, a fixed mark with which said index is made to register for direct firing; a movable mark 85 with which the index is made to register when the sight is aimed at a point of different height than the point to be fired at; a drive for setting the sight to the firing angle, and a gearing positively connected to said 90 drive for giving said index and said movable mark an adjustment relative to each other, the amount of said adjustment being inverse to the range, said gearing having a revolute member and means for turning 95 said member an angle corresponding to the firing angle; a carrier for said movable mark, said carrier being coaxially mounted with said index, said carrier having teeth, a pinion meshing with said teeth; and a cam 100 member positively connected with said drive, a sliding rod engaging with said cam member, and gearing connection between said rod and said pinion.

In testimony whereof the foregoing specification is signed in the presence of two witnesses. 105
